[57] CLAIM

The ornamental design for a closet shelf, as shown.

DESCRIPTION

FIG. 1 is a perspective view of the closet shelf showing my new design;

FIG. 2 is a front elevational view thereof;

FIG. 3 is a rear elevational view thereof;

FIG. 4 is an enlarged left side elevational view thereof, shown broken away for ease of illustration;

FIG. 5 is a top plan view thereof, the bottom being unornamented.

FIG. 4
